UNITED STATES PATENT OFFICE.

GEORGE F. A. OCHS, OF NEWARK, NEW JERSEY.

RAILROAD-SPIKE AND LOCK.

1,353,843.

Specification of Letters Patent. Patented Sept. 28, 1920.

Application filed January 29, 1920. Serial No. 354,841.

To all whom it may concern:

Be it known that I, GEORGE F. A. OCHS, a citizen of the United States of America, residing at Newark, in the county of Essex 5 and State of New Jersey, have invented new and useful Improvements in Railroad-Spikes and Locks, of which the following is a specification.

The object of the invention is to provide 10 a railroad spike, particularly adapted for use in connection with composite ties wherein metal marginal plates are used in connection with a filler of fibrous material, whereby the displacement or the loosening 15 of the spikes due to the jarring or vibration incident to travel over the rails will be prevented, and yet wherein the removal of the spikes to permit of replacing or repairing the rails or ties is facilitated, and the spike is 20 adapted for use in connection with the rails at switches as well as on the main line, and with this object in view the invention consists in a construction and combination of parts of which a preferred embodiment is 25 shown in the drawing, wherein:

Figure 1 is a perspective view of a composite tie provided with seats for the reception of the improved spike.

Fig. 2 is a transverse section on the plane 30 indicated by the line 2—2 of Fig. 1 showing a spike in operative position in the tie and in engagement with a rail supported thereby.

Fig. 3 is a detail view of the spike.

Fig. 4 is a similar view of one of the locking dogs.

The tie in connection with which the spike is preferably used is of the composite type consisting of the top and bottom plates 10 and 11 between which in layers or otherwise is arranged a fibrous filler 12 preferably paper layers treated with creosote held in place by transverse rivets 13 or the equivalents thereof, the top plate being provided 45 with spike seats 14 in proper positions for the reception of spikes 15 designed to secure in proper position upon the tie a track rail 16 of any conventional or preferred form, the head 17 of the spike being adapted to 50 overlap the foot or base 18 of the rail in the ordinary way.

The seats 14 are preferably extended only through the top marginal plate of the tie to the end that the spike inserted therein may 55 be driven into the fibrous filler and in order to secure a proper engagement of the

shank with the filler the former may be provided at and near its penetrating end with serrations 19 having abrupt upper shoulders 20 to resist withdrawal of the spike and 60 thus serve to interfere with the upward displacement thereof.

As a further means, however, of insuring the proper engagement of the spike with the tie it is provided with one or more lateral 65 shoulders 21 arranged near the plane of the head 17 and adapted to pass through the top marginal plate 10 of the tie for engagement by one or more dogs 22 mounted in suitable cavities adjacent to the under surface of the 70 plate 10 and yieldingly held in position to engage the shoulders by means of springs 23. Said dogs are preferably provided with stems 24 upon which the springs are fitted when the latter are of the coiled type 75 indicated in the drawing, while projecting upwardly from the body portions of the dogs and extending through guide slots 25 in the top plate are studs 26 which being accessible from the under surface of the tie 80 may be actuated to disengage the dogs from the shoulders of the spike when it is necessary to withdraw the latter for the purpose of repairing or replacing a rail or tie or otherwise repairing the road bed. 85

The shank 27 of the spike below the plane of the shoulders 21 is beveled to repress the yielding dogs as the spike is driven to place with its head in engagement with the base or foot of the rail, it being obvious that the 90 dogs will spring into engaging relation with said shoulders as soon as the spike reaches its proper position, while above the plane of said shoulders 21 the neck 28 of the spike is preferably rectangular in form with its surfaces parallel with the length of the spike. 95

It will be understood moreover that whereas the illustrated spike is provided with a shoulder 21 at each side, and oppositely located dogs are mounted in the tie for engagement respectively with said shoulders, the duplication of these features serves merely as an additional security inasmuch as the engagement of a single shoulder by a corresponding dog will under normal conditions insure the retention of the spike in proper relation with the tie and rail. 100

What is claimed is:

1. The combination with a composite tie having a top plate and a fibrous filler, of a 110 spike for penetrating said plate and filler and having a lateral shoulder, and a spring-

- actuated dog housed in the tie beneath the said plate for engagement with the shoulder when the spike is in its operative position.
2. A railway tie of the composite type having a top plate provided with a spike opening and a fibrous filler, of a spike having its shank provided with a lateral shoulder, and a spring-actuated dog mounted in a cavity in the tie adjacent to the marginal plate and provided with an upstanding stud operating in a slot in said plate for facilitating the retraction of the dog to release the spike.
- 5
- 10
3. The combination with a composite tie having a top plate and a fibrous filler, and yielding locking dogs in operative relation with a spike seat in said plate, of a spike provided with terminal serrations and having at an intermediate point in its shank lateral shoulders for engagement by 15 said dogs, the portion of the shank extending downwardly from said shoulders being beveled for repressing the dogs as the spike is driven into the tie.
